UNITED STATES PATENT OFFICE.

WILLIAM SCHIMPF, OF SHENANDOAH, PENNSYLVANIA, ASSIGNOR OF ONE-
THIRD TO O. A. KEIM, OF SAME PLACE.

CIRCULATING-BOILER.

SPECIFICATION forming part of Letters Patent No. 325,977, dated September 8, 1885.

Application filed May 11, 1885. (No model.)

To all whom it may concern:

Be it known that I, WILLIAM SCHIMPF, of Shenandoah, in the county of Schuylkill and State of Pennsylvania, have invented certain new and useful Improvements in Circulating-Boilers; and I do hereby declare the following to be a full, clear, and exact description of the invention, such as will enable others skilled in the art to which it pertains to make and use the same.

10 My invention relates to circulating boilers adapted, primarily, for steam heating apparatus, the object being to provide a construction of boiler that will greatly facilitate the heating of the water and generation of steam.

15 The invention consists in the features of construction and combinations of parts hereinafter fully described, and pointed out in the claim.

20 In the accompanying drawings, Figure 1 represents an end view, partly in section, of a boiler constructed in accordance with my invention. Figs. 2 and 3 illustrate parts in detail.

25 A represents the outer jacket or casing of the boiler, provided with a smoke-exit, a.

The fire-box B is preferably circular or cylindrical in form, and consists of an inner shell, C, and an outer shell, C'. These shells 30 are secured together at top and bottom by rings D, to which the shells are riveted to form an annular water-space, E. The fire-box is formed with a suitable feed-opening, e, and door F, said opening being bounded by a frame, f, secured in a water-tight manner to the shells of the box.

35 G represents the boiler proper, arranged above the fire-box, and formed with downwardly-projecting extensions g g, surrounding the fire-box.

40 Across the top of the fire-box is arranged an inverted-T pipe, H, whose horizontal portion h communicates with the water-space E of the fire-box, while its vertical portion h' extends into the boiler.

45 I represent short transverse pipes connecting the lower portions of the boiler-extensions g g with the adjacent parts of the water-space of the fire-box.

The boiler G is provided with a steam-exit, g'.

50 It will be apparent that the water contained in the annular space E of the fire-box will be quickly heated and will readily pass or circulate to the boiler. As represented by the 55 arrows in the drawings, the fire and heat will pass downwardly around the boiler-extensions g g, and thence upwardly over the top of the boiler to the chimney a, thus practically surrounding the boiler and its contained water 60 and serving to quickly generate steam.

Having fully described my invention, what I claim as new, and desire to secure by Letters Patent, is—

65 In a circulating-boiler, the combination, with the boiler having downwardly-projecting extensions, of the fire-box consisting of two shells and connecting-rings forming the water-space, an inverted-T formed pipe connecting the fire-box water-space with the boiler proper, 70 and side pipes connecting said water-space with the extended sides of the boiler, substantially as described.

75 In testimony whereof I have signed this specification in the presence of two subscribing witnesses.

WM. SCHIMPF.
